UNITED STATES PATENT OFFICE.

FRANK JOSEPH STUART, OF ST. LOUIS, MISSOURI.

METHOD OF FORMING HEATER ELEMENTS FOR LIQUID-HEATERS.

1,322,073.

Specification of Letters Patent.

Patented Nov. 18, 1919.

Application filed August 22, 1917. Serial No. 187,708.

To all whom it may concern:

Be it known that I, FRANK J. STUART, a citizen of the United States, residing at St. Louis, State of Missouri, have invented certain new and useful Improvements in Methods of Forming Heater Elements for Liquid-Heaters, of which the following is a specification.

This application includes matter divided 10 from my copending application, filed November 10, 1916, Serial Number 130,591, and to that extent is a continuation of said earlier application.

The invention has for an object to provide a suitable electrical heater unit adapted 15 to use in liquid heating apparatus. It is a particular aim of the invention to give an efficient and durable construction of heating coil, whereby the complete device may be 20 produced at a very low cost. To this end, a special method of building up and forming the heater coil has been evolved, as well as an especially desirable mounting for such a coil by which it is adapted to be introduced into 25 a receptacle or chamber in which liquid is to be heated.

Additional objects, advantages, and features of invention will appear from the disclosure of one embodiment of the invention 30 as hereinafter described, and shown in the drawings, wherein,

Figure 1 is an elevation of a coil as applied to a heater for motor vehicle radiators,

Fig. 2 is a similar view of the appliance, 35 with a different mounting;

Fig. 3 is a detail of the mounting of the appliance,

Fig. 4 is a detail of the structure of the coil,

Fig. 5 is a detail of a bushing element,

Fig. 6 is a detail of a terminal connection and mounting for the coil.

Fig. 7 is a vertical sectional view of a modification of the appliance.

There is illustrated in dotted lines a cylindrical heater casing 16, having large screw threads 17 throughout its length, this casing being open at its lower side, and having an integral annular crown piece 18 at the upper end, from which there extends downwardly a drain tube 19 of cylindrical form which may be located slightly eccentric to the casing, and project a distance below the casing proper. The lower end of the casing 55 is closed by a plate 20, engaged slidably over the projecting lower end of the tube 19, and held snugly against the end of the casing

16 by means of a nut 21 secured on to the lower end of the tube 19. Fitted in the lower end of the tube there is an ordinary 60 drain cock 22. Between the plate 20 and the casing a suitable heat insulating body 23 may be disposed. Mounted upon the plate 20 there is a helical heating coil 24, having the lead wires 25 extended therefrom laterally through opposite sides of the casing as indicated in Fig. 2, or extended downwardly through the plate as shown in Fig. 1. The heating coil of Fig. 1. comprises a core element 26 of sufficient rigidity to hold the 70 coil in proper form and prevent undue distortion or damage thereto by vibration during the first stages of manufacture, and to afford a good footing or base for its mounting, the core in the present instance comprising a heavy steel wire, around which a covering of suitable non-conducting and heat resisting material 27 such as asbestos is engaged, upon which in turn the heating coil proper is wound. The heating coil 33 80 stops short of the ends of the wire 26 and its covering 27, and the ends of the supporting wire 26 and covering are bent into suitable eyes at 28, and secured to the plate 20 by means of screws 29. The lead wires 30 85 are engaged in suitable bushings 31, where they are led in through the casing or the plate 20, as the case may be, and in Fig. 5 there is shown a form of bushing the inner part of which is longitudinally slotted in a 90 number of places circumferentially spaced, and the inner part of the bushing tapered and threaded, so that when screwed into the threaded opening in the plate 20 the sides of the bushing will be compressed so as to grip the wire 30 or its insulation, and hold it securely against loose movement. The wire 30 is connected to the end of the heating coil 33 in any customary manner, within 95 the casing.

In the production of the coil, suitable lengths of wire 26 and its jacketing are provided, upon which the heating wire 33 is wound. The ends of the wire 33 being temporarily secured after winding, the heating element is then bent into the desired shape, as shown, for instance, at 36 in Figs. 1 and 2. After being bent to this shape, the complete coil is then dipped in a paste of a suitable clay, cement, or other material, of such consistency that when the surplus is shaken or drained off, a suitable coating is left upon the coil, this paste material being of a suitable character to become hardened under 100 105 110

the effect of heat, or otherwise, and being a non-conductor of electricity, but of a character to readily radiate and conduct heat. Potters clay has been used for the purpose 5 with satisfactory results. This has the effect of further stiffening and supporting the upper parts of the element.

In assembling the device, in the form shown in Fig. 1, the coil after being dipped 10 or otherwise coated with the stiffening insulation, is first mounted upon the insulating body 23 and the plate 20, the lead wires 30 then extended through the bushings in the plate 20, and connected to the ends of 15 the heating coil wire, after which the plate is adjusted in position on the bottom of the casing 16, and secured by the nut 21. The cock 22 may then be put in place and the device is ready for attachment to the radiator. In the form shown in Fig. 1, the complete coil and its connections may be assembled on the plate 20, before introduction into the casing 16, as will be readily apparent. The coil 36 is formed with an upstanding 20 portion 35 from the upper end of which the coil is continued downwardly, the part 35 being located closely within the coil 36 at one side.

A further simple construction for the device which may be considered preferable is shown in Fig. 2, wherein there is shown a cylindrical casing element 40. Within the element 40, a coil 44 is mounted, which in the present instance need not have the central core wire 26 before mentioned if undesired, the coil being supported by means of a pin 45, driven through suitable diametrically alined openings in the upper part of the element 40, and engaging under one 35 of the upper helices of the coil 44. The ends of the resistance wire 46 of the coil are extended through suitable openings at opposite sides of the tube, at its lower end, in which bushings 47 may be fitted similar 40 to the bushing 31, if desired. The wires 46 may be connected in any desired manner 45 with an energizing circuit as will be readily understood.

Various methods for mounting the coil in 50 a liquid container may be employed, in addition to those before described, and it may be found preferable to mount the coil upon its support and make the connections between the heating coil and insulated binding posts before dipping the appliance, and 55 then dipping the mounted coil so that its base portion and the terminal ends of the heating coil proper will all be covered by the coating of outer insulating material, the 60 subsequent hardening of which will protect all parts of the device from contact with the liquid which may circulate about the coil. An example of this method is illus-

trated in Fig. 6, wherein a coil is mounted upon a body 50, which may comprise the 65 wall of a receptacle or a suitable base plate separate therefrom, the terminal portion of the supporting element in the coil being formed in the same manner as shown in Fig. 1, and as previously described. The securing 70 bolts 51, however, are insulated from the plate 50 in a suitable manner, and the terminal portions of the core element of the coil are also insulated therefrom by means of a sheet of insulating material 52. The 75 terminals of the heating wire are engaged under the heads of the bolts 51, suitable washers 53 being disposed under the heads to clamp the insulating material around the stiffening wire of the coil. After being secured in this way, either temporarily or permanently, the coil is dipped so that the exterior coating of insulating material 54 will cover the bolt heads and the terminal 80 ends of the heating wire, as well as the sheet 52 of insulating material. The sheet 52 may be of porcelain or india rubber, as found 85 most desirable.

The body 50 is formed with holes larger 90 than the bolts 51, so that the latter may not touch the body 50, and the bolts are held centered in the openings by means of simple bushings 55, nuts 56 being engaged on the outer ends of the bolts to hold them in place. Binding nuts 57 may also be engaged upon the outer ends of the bolts for connecting suitable wires thereto.

If desired, the plate 50 may have a drain cock 58 fitted thereto as shown in Fig. 7, and be secured to the bottom of a casing 100 59 of considerably larger diameter, having a small threaded nipple at the upper end adapted to be screwed into the usual small outlet opening of a radiator, in place of the 105 usual drain cock.

What is claimed is:

The method of forming a heating coil or resistance element consisting in winding upon a comparatively rigid wire jacketed with non-conducting material, a suitable resistance wire to form a heating coil upon the said jacket, the winding stopping short of the end of said jacket and inclosed wire, then bending the assembly described into the shape finally desired, and dipping the parts 110 having said winding thereon in a thin paste of a material adapted to harden by the action of heat or otherwise, and which is a good conductor of heat.

In testimony whereof I have affixed my 120 signature in presence of two witnesses.

FRANK JOSEPH STUART.
